US00D536325S

(12) **United States Design Patent** (10) **Patent No.:** **US D536,325 S**
Kim et al. (45) **Date of Patent:** **** Feb. 6, 2007**

(54) **PORTABLE PHONE**

(75) Inventors: **Young-Sae Kim**, Palo Alto, CA (US);
Chi-Young Ahn, Seodaemun-Gu (KR);
Beom-Ku Han, Seoul (KR);
Chang-Hwan Hwang, Goyang-Si (KR)

(73) Assignee: **Samsung Electronics Co., Ltd.**,
Suwon-si (KR)

(**) Term: **14 Years**

(21) Appl. No.: **29/234,759**

(22) Filed: **Jul. 22, 2005**

(30) **Foreign Application Priority Data**

Jan. 26, 2005 (KR) 30-2005-0002602

(51) **LOC (8) Cl.** **14-03**

(52) **U.S. Cl.** **D14/138**
